JAW-INSERT PLIERS

Woodford J. Crump, Southgate, Calif., assignor to Aircraft Tools, Inc., Los Angeles, Calif., a corporation of California

Application March 6, 1956, Serial No. 40,479

Term of patent 14 years

(Cl. D54—13)

I claim:

The ornamental design for a jaw-insert pliers, substantially as shown.
